HAND TOOL FOR CRIMPING ELECTRICAL CONNECTORS ONTO CONDUCTORS

Henry W. Demler, Lebanon, Pa.

Application April 20, 1956, Serial No. 41,147

Term of patent 14 years

(Cl. D54—13)

Figure 1 is a front perspective view of a hand tool for crimping electrical connectors onto conductors showing my new design; and

Figure 2 is a rear perspective view thereof.

I claim:

The ornamental design for a hand tool for crimping electrical connectors onto conductors, substantially as shown.
